UNITED STATES PATENT OFFICE.

SAMUEL ANDERSON MIDDLEBROOKS, OF MACON, GEORGIA.

CARBURETER.

1,294,513.

Specification of Letters Patent. Patented Feb. 18, 1919.

Application filed September 7, 1917. Serial No. 150,244.

To all whom it may concern:

Be it known that I, SAMUEL A. MIDDLEBROOKS, a citizen of the United States, and resident of Macon, in the county of Bibb and State of Georgia, have invented new and useful Improvements in Carbureters, of which the following is a specification.

My invention relates to carbureters, and has particular reference to that class of carbureters used in connection with internal combustion engines.

An important object of the invention is to provide in a device of the above mentioned character a means which will make possible the using of heavy hydro-carbon liquid as a fuel to produce a result equal in effect to that produced in the use of the lighter hydro-carbon liquids now commonly employed as a fuel.

20 A further object of the invention is to provide in a device of the above mentioned character a means whereby the hydro-carbon liquid may be uniformly heated prior to the exposure of the same to an air current in its course of travel through the carbureter and into the explosion chamber of an internal combustion engine.

25 A further object of the invention is to provide in a device of the above mentioned character a means for heating the air current prior to the contracting of the same with the hydro-carbon liquid and a means whereby the heated air, after having become saturated with the volatilized liquid, 30 may be kept at a uniform temperature in its course of travel into the combustion chamber of an internal combustion engine.

35 A further object of the invention is to provide in a device of the above mentioned character a means whereby the air current and volatilized liquid may be uniformly mixed thereby forming a highly homogeneous mixture, rendering the explosive charge, when exploded within the cylinder 40 of an internal combustion engine, more effective than would otherwise be possible.

45 Other objects and advantages of the invention will be apparent during the course of the following description.

50 In the accompanying drawings forming a part of this specification and in which like numerals are employed to designate like parts through the same,

Figure 1 is a side elevation of the device 55 embodying my invention,

Fig. 2 is a view of the same, showing a

portion in central vertical longitudinal section and a portion in elevation,

Fig. 3 is a central vertical sectional view of a carbureter, and,

Fig. 4 is a horizontal sectional view taken on line 3—3 Fig. 3.

In the drawings, wherein for the purpose of illustration is shown a preferred embodiment of my invention, the numeral 5 designates an exhaust manifold having openings or ports indicated by the numeral 6 which are adapted to register with the intake ports of an internal combustion engine (not shown). Within the exhaust 70 manifold 5 there is disposed an intake manifold 7 adapted to open into the ports or openings 8 which are adapted to register with the intake openings or ports of an internal combustion engine. This intake 75 manifold may be cast integral with the exhaust manifold or formed in any other desired manner. One end of the exhaust manifold 5 is provided with a nipple 9 having screw threads thereupon which are 80 designed to engage internal screw threads of a pipe (not shown), the pipe being adapted to carry the exhaust gases from the exhaust manifold to any desired and remote point. One end of the exhaust manifold is provided with a pipe 10 and serves to connect the interior of the exhaust manifold with a jacket provided by a carbureter indicated as a whole by the numeral 11. The carbureter 11 comprises a bowl 90 12 which is provided with a wall 13 spaced therefrom, forming a jacket 14 between the bowl 12 and the wall 13. The bowl 12 is provided with a closure 15 having a depending tubular member 16 secured to the 95 underside thereof, and extending downwardly into the bowl 12. The closure 15 is provided upon its upper side with a conduit 17 the end of which is provided with a sheet metal member 18 secured to the pipe 100 10 and spaced an appreciable distance therefrom on its inner side to allow the passage of air between the pipe 10 and the interior of the member 18. The conduit 17 together with the sheet metal member 18 105 serves as a means for directing heated air taken from around the pipe 10 into the depending tubular member 16 as will herein-after be described. Diametrically opposed to the conduit 17 and positioned upon the 110 closure 15 there is provided a mixture outlet pipe 19 the interior of which is adapted

to communicate with the interior of the depending tubular member 16. Within the tubular member 16 there is disposed a removable nipple 20, provided at its upper edge with a flange 21, adapted to seat itself upon the seats 22 and 23, carried within the mixture outlet pipe and conduit respectively. The lower end of the depending tubular member 16 is provided with a removable valve seat 24, adapted to receive a needle valve 25 carried by a stem 26 which is provided at its upper end with screw threads 27, engaging interior screw threads carried within a depending portion 28 of a removable cap 29, secured to the exterior of the conduit and gas outlet pipe as shown. A portion of the needle 26 extends to an appreciable distance above the cap 29 and is provided at its upper end with a lever 30, by means of which a rotary motion may be imparted to the stem 26, whereby a reciprocatory movement may be imparted to the valve 25 under the influence of the screw threaded portion of the stem 26 with the coacting internal screw threads of the depending portion 28. A link 31 serves to connect the lever 30 with an arm 32, carried by the stem 33 of a valve 34, which valve is arranged within the mixture outlet pipe 19 as clearly shown in Fig. 2. The link 31 serving to either open or close the valve 34 simultaneously with the valve 25.

Within the jacket 14 of the carbureter there is disposed a coil of fuel conducting pipe 35 which enters through the wall 13, as shown at 36, and protrudes therefrom through the wall as shown at 37. The exterior portion 38 of the pipe 35 is connected with a passage way 39, provided within an enlarged portion 40 of the wall of the depending tubular member 16 as shown in Fig. 2. At the lower end of the passage 39 there is provided a valve 41 mounted within a removable seat 42 which is held in position as shown in Fig. 3, by means of screw threads. This valve is adapted to be reciprocated by means of a float 43 carried within the bowl 12, the action of which is governed by the quantity of fuel contained within the bowl as will hereinafter be described.

The exhaust manifold 5 is provided at its lower side approximately intermediate the ends thereof with an extended portion 44, having provided therein a passage 45 affording communication between the carbureters 11 and 48, the flow of mixture through this passage being governed by a rotary valve 46, the action of which will hereinafter be described. The lower end of the extended portion 44 is provided with a coupling 47 which serves to connect the outlet pipe 19 with an auxiliary carbureter indicated by the numeral 48. A rotary valve 49 is disposed within the coupling 47 and serves

to sever communication between the carbureter 11 and the auxiliary carbureter 48, one of which carbureters is thereby brought into communication with the interior of the intake manifold 7 as shown in Fig. 2. This valve is adapted to be operated by means of a lever 50 connected thereto and shown in Fig. 1.

A pipe 51 is connected to the wall 13, which pipe is in turn connected to the exhaust manifold 5 as clearly shown in Figs. 1 and 2. A pipe 52 is secured to the pipe 51 and spaced an appreciable distance therefrom on its inner side to allow the passage of air between the pipe 51 and the pipe 52, the pipe 52 being in turn connected to the auxiliary carbureter 48.

The exhaust manifold 5 is provided on its upper side with a dome 53 having disposed thereupon a cap 54 which serves as a closure for the same. Within the dome 53 there is provided a governor indicated as a whole by the numeral 55. This governor is connected to the rotary valve 46 by means of a stem 56 housed within a casing 57 carried within the exhaust manifold 5. The governor 55 is adapted to be operated by a flexible shaft 58 connected by any suitable means to a rotating member of an internal combustion engine for the purpose of operating the same.

To the arm 32 there is connected a link 62 which in turn is connected to an arm 63 similar to that indicated by the numeral 32, the arm 63 being operably connected to a valve, not shown, which valve is arranged within the carbureter 48 and identical with the valve indicated by the numeral 34. It is obvious therefore that when the valve 34 is moved the valve to which the lever 63 is connected is likewise moved.

The operation of the device is as follows: When it is desired to start an internal combustion engine with which my device is used, the rotary valve 49 is moved to the position shown in Fig. 2, whereupon gas from the carbureter 48, employing light hydro-carbon as a fuel, preferably gasolene, which is supplied thereto through the pipe 61, is allowed to enter the intake manifold and pass into the combustion chamber of an internal combustion engine. A portion of the hot exhaust gases, escaping from the internal combustion engine through the ports 6 into the manifold 5, is transmitted to the coil of pipe 35, carrying a heavy liquid hydro-carbon fuel, preferably kerosene, by means of the pipes 10 and 51. When the kerosene has become sufficiently heated to cause it to readily volatilize the rotary valve 49 is moved to a position indicated by the dotted line in Fig. 2, whereby communication between the intake manifold 7 and carbureter 48 is severed, and at the same time communication is established between the carbureter 11

and the manifold 7. The valve 25 is then lifted from the seat 24 by rotating the stem 26 by means of the crank 30, allowing fuel to pass from the bowl 11 into the cup 26, of the valve seat 24, through the opening 25. The heated air supplied from around the pipe 10 is transmitted downwardly into the depending tubular member 16 and into contact with the fuel contained within the cup 26. The air after having become saturated with particles of the fuel travels upwardly through the nipple 20, into the outlet 19, and into the intake manifold 7. This mixture is agitated in its course of travel through the outlet 19 by means of a mixer 19' revolvably mounted therein for the purpose of forming a more homogeneous mixture.

The travel of mixture through the outlet 19 is governed by means of the valve 34 which is opened or closed simultaneously with the opening or closing of the valve 25.

The rotary valve 46 serves to govern the flow of mixture into the intake manifold 7. As the engine increases in speed the valve, under the influence of the governor 57, gradually closes thus allowing less fuel to enter the combustion chambers of the engine, thereby decreasing the speed of the same. As the speed of the engine decreases, the valve 46 gradually opens, allowing more mixture to enter the combustion chamber of the engine whereupon the speed of the same will be accelerated.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Claims:—

1. In a carbureter, the combination of a bowl provided with a jacket, a coil of fuel conducting pipe arranged within said jacket, a closure disposed upon said bowl, a depending tubular member carried by said closure, said tubular member being secured at its lower end to the bottom of said bowl, a rib

carried by said depending member, said rib being provided with a passage having communication with said fuel conducting pipe, means for automatically governing the flow of fuel from said pipe through said passage 55 into said bowl, manually operated means for governing the flow of fuel from said bowl into said depending member, means for directing heated air currents downwardly through said depending member, a mixture 60 outlet pipe carried by said closure, means for directing the heated air currents upwardly from said depending member into said mixture outlet pipe, manually operated means for governing the flow of mixture through 65 said outlet pipe, the last named means being simultaneously operated with the means for governing the flow of fuel from said bowl into said depending member and means for directing a heated medium into said jacket. 70

2. In a carbureter, the combination of a bowl provided with a jacket, a coil of fuel conducting pipe disposed within said jacket; a closure for said bowl, a tubular depending member carried by said closure, said member being secured to the bottom of said bowl, a removable valve seat arranged within said tubular member at the lower end thereof, a rib carried by said depending member, said rib being provided with a passage having 80 connection with said fuel conducting pipe, a removable valve seat arranged within said passage, a reciprocatory valve arranged within said seat, a float arranged within said bowl for actuating said valve whereby the 85 flow of fuel from said pipe into said bowl is controlled, a nipple carried by said closure, said nipple depending into said tubular member, a mixture outlet pipe arranged upon said closure, a valve arranged in said 90 mixture outlet pipe, a rotating reciprocatory valve arranged within the first named valve seat, means for operating simultaneously the second and third named valves, means for directing a heated medium into 95 said jacket, and means for directing a heated medium into said tubular member and nipple and mixture outlet pipe.

SAMUEL ANDERSON MIDDLEBROOKS.
